UNITED STATES PATENT OFFICE

149,899

DESIGN FOR A LIP ROUGE APPLICATOR

Zachary Melnikoff, Los Angeles, Calif.

Application April 7, 1947, Serial No. 138,215

Term of patent 7 years

(Cl. D86—10)

To all whom it may concern:

Be it known that I, Zachary Melnikoff, a citizen of the United States and resident of the city of Los Angeles, county of Los Angeles and State of California, have invented a new, original, and ornamental Design for a Lip Rouge Applicator, of which the following is a specification, reference being had to the accompanying drawings, forming part thereof, in which:

Fig. 1 is a perspective view of a lipstick applicator, showing my new design;

Fig. 2 is a bottom plan view of the applicator tip on an enlarged scale;

Fig. 3 is a longitudinal-sectional view thereof;

Fig. 4 is a top plan view of the same;

Fig. 5 is a cross-sectional view taken along the line 5—5 of Fig. 3; and

Fig. 6 is a cross-sectional view taken along the line 6—6 of Fig. 3.

The essential features of my design reside in the portions shown in full lines.

I claim:

The ornamental design for a lip rouge applicator, as shown and described.

ZACHARY MELNIKOFF.
